UNITED STATES PATENT OFFICE.

JAMES H. EDMONDS, OF LOS ANGELES, CALIFORNIA.

LIVING-APARTMENT.

944,021.

Specification of Letters Patent. Patented Dec. 21, 1909.

Application filed March 24, 1909. Serial No. 485,538.

To all whom it may concern:

Be it known that I, JAMES H. EDMONDS, a citizen of the United States, residing at Los Angeles, in the county of Los Angeles and State of California, have invented a new and useful Improvement in Living-Apartments, of which the following is a specification.

The principal object of my invention is to 10 provide a living apartment with the ordinary necessities of such an apartment in the most compact and convenient space possible.

Other objects of the invention will appear hereinafter.

15 My invention comprises a living apartment or room provided with a built-up structure therein which provides storage space for domestic use; storage space for wearing apparel, and storage space for a 20 bed or other sleeping utility.

25 My invention also embodies the arrangement and combination of parts as herein-after fully set forth and illustrated in the accompanying drawings, of which—

30 Figure 1 is a view of a portion of such living apartment provided with a built-up structure embracing the elements employed by me in my improvement. Fig. 2 is a longitudinal vertical section of the built-up structure, on the line x^2-x^2 in Fig. 3. Fig. 3 is a vertical cross section of the same, on the line x^3-x^3 in Fig. 2. Fig. 4 is a plan showing one manner of adapting the built-up structure to an apartment. Fig. 5 is a 35 plan showing another arrangement of the living apartment.

In a living apartment, which may be square or of other shape according to the requirements of the building in which the 40 apartment is situated, I provide a built in construction serving the three-fold purpose of a means for inclosing a bed when the same is not in use; as a closet or plurality of closets, and as a means of dividing the apartment wholly or partially into different rooms.

The built-in construction comprises a casing 1, rectangular in cross section and extending preferably from the floor 2 to the 50 ceiling 3 of the apartment. This casing is formed at one side and at the bottom thereof with an opening 4 of sufficient width and height to enable a horizontal bed 5 to be pushed into said opening, and at another 55 side of the casing there is provided a doorway 6 preferably extending to the floor, and

of sufficient size to enable access of a person to the interior of the casing, said doorway having a suitable door 7, and a transom 8 being preferably provided over the doorway 60 for ventilation. The space 9 within the lower portion of this casing is left clear for reception of the bed as stated. Above this bed receiving space the casing is preferably provided interiorly with means adapting the 65 interior of the casing for use as a closet. A preferred construction for this purpose is that shown in the drawings wherein this interior portion of the casing is divided by transverse partitions 10, 10' and longitudinal partition 11 into closet compartments 12, 13, 14 and 15. The closet 12, which is on the side at which the bed enters and leaves the casing, may be formed as a china closet or book case. The closet 13 occupies 70 the major portion of the space at the rear of the china closet and is provided with shelves 16 extending around the same and preferably with bars or other devices 17 extending over the space between the shelves 80 to enable clothing, etc., to be hung in said space. In case it is desired to close the bed receiving space 9 a movable screen 19 may be provided resting on ledges 20 and preferably folding on hinges as at 21 to enable it 85 to be folded up out of the way when not in use. This screen is preferably made of fabric, such as cloth or other suitable material, supported on a suitable frame so as to facilitate ventilation of the bed receiving 90 space and of the closet. The closets 14 and 15 may be used for other purposes, such as for hat-boxes, linen or the like. Suitable drawers 22 may be provided for these closet compartments. 95

The opening at the front of the bed receiving space 9 at the lower part of the casing 1 is provided with hinged doors or closure means 23, each door having portions hinged together at 24 so as to fold into compact space when open. The bed may be provided with a projection 25 engaging elevated guides 26 on the floor 2 when the bed is shoved back into the space 9, so as to guide the bed into proper position within said 100 space. Said bed may be further provided with a projection 28 which, when the bed is shoved clear in, engages with an upwardly extending arm 29 on a ventilator flap or means 30 to open the said ventilator. When 105 the bed is removed from the space in the casing the flap closes the ventilator opening. 110

I do not confine myself to guides on floor as they may be placed elsewhere.

The advantages of the above described construction considered as a bed container are, first, that it utilizes all of the space above the bed receiving space; second, that by removing the horizontal screen 19 access may be obtained to practically the whole of the bed receiving space and the closet space above the same when the bed is removed; a person being permitted to enter by simply folding or removing this screen and stepping into the closet space 13 and being then able to brush and sweep the interior of such space and the bed receiving space; third, there is no danger of any one being shut into this bed receiving space as the egress therefrom is always possible by means of the door 7. The bed receiving construction above described also presents certain advantages in connection with its arrangement in a living apartment as shown in Figs. 4 and 5. In Fig. 4 the space appropriated to a living apartment is divided by a partition wall 31 and by cross walls 32, 33 between said partition wall and the inside wall 34 of the apartment so as to form a kitchen space 35, a bath room space 36 and a light court 37, and a closet 38 between said spaces. The space at the other side of said main partition is larger than the space containing the kitchen, etc., being the main living portion of the apartment and opening by a door 39 into the hall 40. In the form shown in Fig. 4 the casing 1 is built into the said living portion of the apartment in such manner as to leave a space extending completely around the said casing between the said casing and the walls of the apartment, the casing dividing the larger portion of the apartment into a main chamber 45 and subsidiary chambers 46, 47, 48. The spaces 46, 47 which extend between the said casing and the inside wall of said living apartment may be used as hallways, the space 46 serving as a reception hall, and the space 48 on the other side between the said casing and the outside wall of the apartment may be utilized as a dressing room, a partial partition 42 being provided to cut off this portion from the living room proper 45. Curtain poles 41, 43 may be provided between the reception hall 46 and the main chamber 45, and between the dressing room 48 to support portieres as indicated in dotted lines in Fig. 1. The front of the casing 1 at which the bed receiving space 9 opens, faces into the living room proper 45. It will be seen that in this construction the bed containing casing 1 serves as a means for dividing off the living apartment in such manner as to fully utilize the space and provide for convenient access between different portions of the apartment. Another convenient arrangement is shown in Fig. 5 wherein the bed containing casing 1

is built against the inside wall of the apartment, eliminating one hall space, the construction being otherwise as above described.

What I claim is:

1. In a living apartment, a built-in casing having a bed receiving chamber with an opening at one side thereof adjacent the floor of the apartment, adapted to permit the movement of a bed horizontally into and out of said receiving chamber, said casing being provided at another portion thereof with means for access into the said chamber within the interior of the casing, said means extending from the level of the floor of said apartment upward and affording access to the bed when in said bed receiving chamber and to the space within said chamber above said bed, said chamber within said built-in casing being free and unobstructed from floor to ceiling. 85

2. In a living apartment, a casing having a floor provided with a ventilating opening and having ventilating means at the upper portion of the casing, a movable closure for said opening, said casing having a bed receiving space adjacent said floor, in combination with a bed removably inserted in said bed receiving space and provided with means engaging the said closure of the opening in the floor to open the said opening when the bed is inserted within the casing and to close the said opening when the bed is removed from the casing. 90

3. In a living apartment, a casing having a floor provided with a ventilating opening, a movable closure for said opening, said casing having a bed receiving space adjacent said floor, in combination with a bed removably inserted in said bed receiving space and provided with means engaging the said closure of the opening in the floor to open the said opening when the bed is inserted within the casing and to close the said opening when the bed is removed from the space. 105

4. In a living apartment having a single common floor, a built-in casing forming a central chamber within said apartment and dividing said apartment into two spaces, said casing provided at one side of the floor level with an opening for the movement of a horizontal bed into and out of said central apartment, and provided with an opening extending upward from substantially the floor level into said central chamber from the room or space formed at another side of said casing, said second opening affording access both to the bed when in said central chamber and to the space of said central chamber above said bed, and removable means for closing said first opening. 115 120 125

5. In a living apartment, the combination of a casing extending from the floor to the ceiling to form a closet, an opening through a partition wall at the lower front end of said casing and adjacent the floor thereof, 130

a horizontal bed removably inserted in said closet through said opening, a guide secured upon the floor within said casing, downwardly extending guide means attached to 5 and carried by the bed, and arranged to engage with and move along said guide, whereby the bed is guided into and out of said closet, and a secondary opening through another portion of the casing extending 10 from the floor of said closet upward, affording a passage way to admit the entrance of a

person into the closet or access to the bed when in said closet, the said closet provided with a single unitary chamber free and unobstructed from floor to ceiling.

15

In testimony whereof, I have hereunto set my hand at Los Angeles, California, this 17th day of March 1909.

JAMES H. EDMONDS.

In presence of—

F. M. TOWNSEND,

FRANK L. A. GRAHAM.
